J. W. HIGGINS

COTTON CHOPPER AND WEEDEER ATTACHMENT FOR CULTIVATORS

Filed July 9, 1925

J. W. Higgins. Greenfor

9/24 Clarence A. O'Brien
Attorney

UNITED STATES PATENT OFFICE.

JOHN WARREN HIGGINS, OF MERKEL, TEXAS.

COTTON CHOPPER AND WEEDEER ATTACHMENT FOR CULTIVATORS.

Application filed July 9, 1925. Serial No. 42,517.

To all whom it may concern:

Be it known that I, JOHN WARREN HIGGINS, a citizen of the United States, residing at Merkel, in the county of Taylor and State of Texas, have invented certain new and useful Improvements in a Cotton Chopper and Weeder Attachment for Cultivators, of which the following is a specification.

This invention relates to improvements in weeder, and has for its principal object to provide one which may be attached to a riding cultivator whereby the operator of the cultivator may move the weeder into an operative or inoperative position.

Another important object of the invention is to provide the weeder attachment for cultivators, which may be readily and easily attached to one of the front plow standards, the same including an elongated rod portion which is rotatably supported on the cultivator, a laterally extending blade being carried by the lower end of the rod, a handle being provided in the upper end of the rod for rotating the same whereby the blade is moved into an operative or inoperative position, the weeder in no way interfering with the use of the cultivator when the latter is in operation.

A further object is to provide a weeder attachment for cultivators of the above mentioned character which is simple in construction, inexpensive, strong and durable and further well adapted to the purpose for which it is designed.

Other objects and advantages of the invention will become apparent during the course of the following description taken in connection with the accompanying drawing:

In the accompanying drawing forming a part of this application and in which like numerals designate like parts throughout the same:

Figure 1 is a side elevation of the weeder attachment, showing the same associated with the plow standard and beam.

Figure 2 is a front elevation, and

Figure 3 is a top plan view.

In the drawing wherein for the purpose of illustration is shown the preferred embodiment of my invention, the numeral 1 designates the beam of a cultivator, preferably of the riding type, one of the front plows being shown at 2, and being associated with the lower end of the plow standard

or foot 3, in the manner well known in the art. This plow standard is also secured on the beam in the usual manner.

A bracket 4 is provided at its rear end with the eye portion 5, the forward end of the bracket being detachably secured to the lower portion of the plow standard or foot 3 at a point above the plow 2 by means of the clamping plate 6 and the bolt 7. Extending through the eye portion 5 of the bracket 4 and adapted for rotation therein is a lower portion of an elongated rod 8.

The upper portion of the rod extends through a guide opening 9 provided therefor in the laterally disposed portion 10 of the bracket 11, the latter extending upwardly from the plow beam 1 at a point rearwardly of the plow foot or standard 3, and being secured to the plow beam as at 12. The upper end of the rod 8 terminates in the handle portion 13, and is located at a point adjacent the driver's seat of the riding cultivator (not shown). Detachably secured on the lower end of the rod 8 and extending laterally therefrom is the blade 14, both edges of which are sharpened.

The rod 8 is adjustably supported with respect to the brackets 4 and 11, so that the depth at which the blade 14 is to cut may be regulated through the medium of the collars 16 and 18 respectively. These collars are detachably clamped around the rod 8 on opposite sides of the eye portion of the bracket 4 in the manner clearly illustrated in the drawing. By loosening the collars, the rod 8 may be raised or lowered, and when the collars are tightened after the rod has been properly adjusted, the same will cooperate with the bracket 4 in limiting the vertical movement of the rod.

When the plows of the cultivator are in use, the blade 14 of the weeder is disposed directly behind the plow 2 so as not to protrude beyond the side thereof, and thereby enable the plows to be used in the usual manner without any interference by the weeder. The weeder is moved into operation by actuating the handle 13 so that the rod 8 is turned, causing the blade 14 to swing outwardly to a lateral position such as is shown in Figures 2 and 3, and as the cultivator moves along the surface of the ground, the blade 14 will cut the growing weeds in a simple and efficient manner.

The provision of a weeder of the above mentioned character enables the same to be readily and easily attached on a cultivator without necessitating any alterations with respect to the latter, and the parts are so arranged as to enable the operator of the cultivator to have ready access thereto and control the operation of the weeder at all times.

10 The device may also be used as a cotton chopper for thinning out the cotton to the proper stand for cultivation.

While I have shown the preferred embodiment of my invention it is to be understood that minor changes in the size, shape and arrangement of parts may be resorted to without departing from the spirit of the invention and the scope of the appended claims.

20 Having thus described the invention, what I claim as new and desire to secure by Letters Patent is:—

1. In combination with a plow beam, a plow and the usual foot therefor, of a weeder comprising a vertical rod, a bracket extending rearwardly from the plow foot for supporting the vertical rod, an additional support for said rod extending upwardly from the plow beam, a handle 25 formed on the upper end of the rod, and a cutter blade extending laterally from the lower end of the rod, said rod being adapt-

ed for rotatable movement in said bracket when the handle is operated.

2. In combination with a plow beam, a 35 plow, and the usual foot therefor, of a weeder comprising a bracket carried by the lower portion of the plow foot and extending rearwardly therefrom, an additional bracket attached to the plow beam, an elongated rod extending vertically through said brackets and adapted for rotation therein, a handle at the upper end of said rod for actuating the same, a laterally extending cutter blade at the lower end of the rod, 40 and means for adjustably securing the rod.

3. In combination with a plow beam, a plow, and the usual foot therefor, of a weeder comprising a bracket carried by the lower portion of the plow foot and extending rearwardly therefrom, an additional bracket attached to the plow beam, an elongated rod extending vertically through said brackets and adapted for rotation therein, 45 a handle at the upper end of said rod for actuating the same, a laterally extending cutter blade at the lower end of the rod, and a pair of collars detachably associated with the rod on opposite sides of the first mentioned bracket for holding the rod and 50 the blade in any adjusted position.

In testimony whereof I affix my signature,

JOHN WARREN HIGGINS.
